UNITED STATES PATENT OFFICE.

PIERRE GIRON, OF PARIS, FRANCE.

CAPSULE INTENDED TO CONTAIN COMPRESSED GASES.

No. 903,134.

Specification of Letters Patent.

Patented Nov. 3, 1903.

Application filed August 15, 1906. Serial No. 330,734.

To all whom it may concern:

Be it known that I, PIERRE GIRON, a citizen of the Republic of France, residing in Paris, France, 9 Rue Castex, have invented certain Improvements in the Construction of Capsules Intended to Contain Compressed Gases, of which the following is a full, clear, and exact description, and for which I have applied for Letters Patent in France, dated September 16, 1905, (not issued.)

This invention relates to improvements in the construction of capsules intended to contain compressed gases and having for their object to reduce the cost price of these capsules and render their action more certain.

The capsules in question are more particularly those known as valve capsules, that is to say rechargeable capsules which comprise two distinct principal parts, the receptacle properly so-called and the fitting containing the valve.

Hitherto the body of the receptacle of these capsules has been formed from a metal tube the extremity constituting the bottom being closed by a special rivet forming a tight joint by compressing a washer of appropriate material. The other extremity is contracted for the reception of the valve arranged in a fitting screwed upon a screw-threaded rod fixed by burring over in the orifice of the receptacle.

The improvements which form the object of the present invention have for their especial object to permit of dispensing with the special rivet and the screw-threaded rod employed in forming the capsules referred to above and in the arrangement of the valve in such a manner as to leave the whole of the internal space free for the gas.

The description is given with reference to the accompanying drawing in which:

Figures 1 and 2 show on a large scale in vertical section and external elevation a capsule in accordance with the invention.

The receptacle *a* of this capsule, which may be of any desired capacity, is formed by a series of pressing operations, from sheet steel of appropriate thickness and quality for withstanding the pressure of the gases. These operations are effected in such a manner as to leave a sufficient thickness of metal at the neck or restricted portion of the receptacle for forming on the edge of the neck a screw-thread *b* and a bead *c* comprising internally a chamfer *c'*. The receptacle *a* thus formed is adapted for the reception of the

fitting *d*, by screwing directly upon it and for forming by the intermediary of a washer *e* a joint sufficiently strong for withstanding the fluidity and the high pressure of the gases. When the joint is tightened up, the washer *e* is forced by the undercut annular flange *g* towards the interior of the neck by reason of the chamfer *c'* which prevents it from spreading externally as is the case with capsules at present employed in which the sharp angle of the edges of the neck cut the said washer and thereby cause leakages.

The fitting *d* in which the valve *f* is mounted is constituted in such a manner that the seat of the valve instead of being formed by the outer edges of the fitting is situated as far forward as possible in such a manner that the valve itself provided with its rod is embedded in the interior of the said fitting thus completely freeing the internal capacity of the receptacle *a* which therefore remains available for the gas that it is intended to contain so that the dimensions of the capsule may be reduced to the minimum. Into the lower recess of the closure *d* extends a skirt *s* which forms an extension of the passage *p*. The pressure of the valve head against the edge of this skirt insures a tighter joint than would be the case were it to press merely against the flat web *w* between the upper and lower recesses.

What I claim and desire to secure by Letters Patent of the United States is:—

1. A capsule for compressed gas, comprising a body having a cylindrical neck threaded on its inner face provided with an external bead at the upper edge thereof beveled on its inner face, in combination with a closure for said capsule internally recessed above and below to accommodate a valve and adapted to be screwed into said neck and provided with an annular undercut flange projecting over said bead whereby an interposed washer placed upon the bead is confined and compressed against the entering portion of the closure by reason of the cooperation of said undercut flange and the bevel of the bead, substantially as described.

2. A capsule for compressed gas comprising in combination with a body part having a neck internally threaded to receive the same, a closure externally threaded to enter said neck and internally recessed above and below, with a passage connecting said recesses, a skirt extending into said lower recess and forming an extension of said pas-

sage, a valve normally located in said lower recess and pressing against the lower edges of said skirt, and provided with a stem passing through the passage connecting said recesses, and a head working within said upper recess, substantially as described.

3. A capsule for compressed gas comprising a body having a cylindrical neck threaded on its inner face provided with an external bead at the upper edge thereof beveled on its inner face, in combination with a closure for said capsule adapted to be screwed into said neck and provided with an external undercut flange projecting over said bead, and recessed internally above and below, with a passage

connecting said recesses, a skirt extending into said lower recess, and forming an extension of said passage, a valve normally located in said lower recess and pressing against the lower edges of said skirt, and provided with a stem passing through the passage connecting said recesses, and a head working within said upper recess, substantially as described.

In testimony whereof I have signed my name to this specification, in the presence of 25 two subscribing witnesses.

PIERRE GIRON.
